UNITED STATES PATENT OFFICE.

RILEY CROUCH, OF MAY, TEXAS.

CHURN.

SPECIFICATION forming part of Letters Patent No. 447,399, dated March 3, 1891.

Application filed December 31, 1889. Renewed February 4, 1891. Serial No. 380,146. (No model.)

To all whom it may concern:

Be it known that I, RILEY CROUCH, a citizen of the United States, residing at May, in the county of Brown and State of Texas, have 5 invented a new and useful Churn, of which the following is a specification.

My invention relates to improvements in churns; and it consists in certain novel features hereinafter described and claimed.

10 In the accompanying drawings, Figure 1 is a front view. Fig. 2 is a vertical section of my improved churn, taken on the line xx of Fig. 1.

The supporting-frame consists of the side 15 bars A, on which the platform B is secured, the standards C, rising from the side bars, and the cross-bar D, connecting the upper ends of the standards. The standards are provided near their upper ends with the vertical longitudinal slots E, and the sliding bar F has its ends fitted in the said slots. The 20 said sliding bar is thus guided vertically in its movements and prevented from any lateral motion. The dasher-shaft is stepped at 25 its lower end in the bottom of the churn-body, which rests on the platform B and extends upward through the sliding bar F and the cross-bar D, and a fly-wheel G is secured to the upper end of the said dasher-shaft. The 30 dasher-shaft is further connected by means of the straps H with the sliding bar F and the vertical rods I, extending downward from said sliding bar. These vertical rods I extend 35 downward through the platform B and have their lower ends connected below said platform by a cross-bar J, as shown. A treadle K is mounted between the extended ends of the side bars A and has its inner end resting on the said cross-bar J.

40 The construction and arrangement of the several parts of my device being thus made known, the operation of the same will be readily understood. The churn-body is placed on the platform, with the dasher extending

into the same. The dasher-shaft is then rotated so as to wind the cord thereon, thereby raising the sliding bar F, and consequently elevating the cross-bar J and the treadle. The treadle is then depressed so as to draw the sliding bar F downward through the medium of the cross-bar J and the vertical rods I, as will be readily understood. This downward movement of the sliding bar causes the cord to unwind, and thereby rotate the dasher-shaft. The fly-wheel will attain sufficient 50 momentum to continue the rotation of the dasher-shaft, so as to again wind the cord thereon, and thereby elevate the sliding bar, so that upon again depressing the treadle the former operation will be again repeated. 55

It will be seen that I have provided a churn which can be easily operated and in which the parts are compactly arranged and are strong and durable, and the advantages of the device are thought to be obvious. 60

Having thus described my invention, what I claim, and desire to secure by Letters Patent, is—

The combination of the side bars A, the standards rising therefrom and having the 70 longitudinal slots E, the sliding bar F, having its ends playing in said slots, the dasher-shaft driven by said sliding bar, the cord secured to the dasher-shaft and the sliding bar and adapted to wind around the said shaft, 75 the vertical rods extending downward from the said sliding bar, the cross-bar J, connecting the lower ends of said vertical rods, and the treadle fulcrumed between the side bars A and having its inner end resting on the 80 cross-bar J, as set forth.

In testimony that I claim the foregoing as my own I have hereto affixed my signature in presence of two witnesses.

RILEY CROUCH.
